UNITED STATES PATENT OFFICE.

WILLIAM H. KING, OF NEWARK, NEW JERSEY.

INDICATOR-LOCK.

SPECIFICATION forming part of Letters Patent No. 417,326, dated December 17, 1889.

Application filed October 9, 1889. Serial No. 326,472. (Model.)

To all whom it may concern:

Be it known that I, WILLIAM H. KING, of Newark, in the county of Essex and State of New Jersey, have invented certain new and useful Improvements in Indicator-Locks; and I do hereby declare the following to be a full, clear, and exact description of the invention, such as will enable others skilled in the art to which it appertains to make and use the same.

5 My invention relates to an improvement in door-latches, and particularly to such as are calculated to indicate the condition of the latch from the outside, whether it be open or closed, or, in other words, unlocked or locked; and the object is to provide a means for indicating from the outside of a door whether it is locked or unlocked, and, furthermore, to provide means whereby the latch may be fastened from the inside and the indicator may 15 be set simultaneously therewith to designate the locked or unlocked condition of the latch.

A further object is to provide means for locking the door from either side and for locking it from the inside only in such manner 20 that it cannot be unfastened from without.

With these ends in view my invention consists in certain novel features of construction and combinations of parts, as will be herein-after fully described, and pointed out in the 25 claims.

In the accompanying drawings, Figure 1 is a view of a portion of the door from the outside. Fig. 2 is a similar view from the inside. Fig. 3 is a sectional view through the knobs 30 and spindle. Fig. 4 is a view from the inside with the knob removed, and Fig. 5 is a detached view of the spindle.

A represents a lock, which may be of ordinary or special construction. This lock is secured 40 inside the door in the usual manner, and is furnished with the spring-actuated latch 1 and the slide-bolt 2, as shown, the former being controlled by the knobs and spindle and the latter by a suitable key, after 45 the accustomed manner.

The latch is controlled—that is, withdrawn from the keeper—by turning the spindle 3 on its axis. Said spindle is angular, preferably square, and fitted to the rocking post 4, 50 which engages the latch and counteracts the action of the spring, which normally forces it

outward. The outside knob 5 and the inside knob 6 are secured on the ends of the spindle adjacent, respectively, to the door 7 and the lock A, and by means of them the spindle is rocked and the latch moved. These knobs may be of most any construction and material; but they are preferably stamped and struck up from sheet metal, so as to be hollow and light, and the outside knob 5 is 55 furnished with an opening 8, through which the words "Open" and "Closed" on a disk 9 within may be seen and easily read from the outside when the latch is unfastened or fastened. This disk is turned by means of a 60 small button 10, loosely mounted in the inside knob. Said button is milled or otherwise roughened to facilitate its operation, and a small shaft 11 extends loosely through the spindle and is provided with the angular 65 heads 12 12 on its ends. One of these heads is fitted in a socket 13, formed in the rear of the indicator-disk, and the other in a socket 14, formed for it in the button 10. Stops 15 15 are arranged inside of the knob 6, to limit and 70 define the turns of the button, so that it is only necessary for the operator to turn the button in one direction until it stops to change the word from that displayed through the opening when turned to the other extreme. All of this is 75 done independently of the knobs; and still another feature of my invention consists in locking the knobs to the lock, or at any rate securing them in some effectual manner, so that the latch cannot be moved from the outside. This locking is done simultaneously 80 with the shifting of the indicating-disk and by the same means in the following manner: A pair of pins 16 16 are loosely supported in the shank 17 of the inside knob 6 on opposite sides of the spindle. These engage a cam 85 formed on the shank of the button 10, whereby they are drawn in or forced out. By a turn in one direction they are forced outward, so that they protrude sufficiently to enter the recesses 17' 17', formed for them—half in the loosely-mounted post 4 and half in the lock A—and lock the latch and knobs, and at the same time display the word "Closed" at the opening in the outside knob 100 5. By the opposite turn of the button 10 the pins 16 16 are removed from the recesses 17'

17' and the word "Open" is disclosed. Thus the latch may be secured from the inside at any time, so that it is impossible to open the door from the outside, either by the knobs or 5 by means of a key, and thus, also, is the indicator changed to indicate the condition of the latch.

It is evident that slight changes might be resorted to in the form and arrangement of 10 the several parts described without departing from the spirit and scope of my invention, and hence I do not wish to limit myself to the particular construction herein set forth; but,

15 Having fully described my invention, what I claim as new, and desire to secure by Letters Patent, is—

1. The combination, with a lock-spindle and knobs and an indicator-disk in one of said 20 knobs, of locking devices for locking the spindle against movement, and means for turning the disk and simultaneously locking or unlocking the spindle, substantially as set forth.

2. The combination, with a pair of knobs, 25 and spindle upon the ends of which the knobs are secured, of an indicator in one of the knobs and a button in the other, having connection with the indicator, whereby the latter is turned, substantially as set forth.

30 3. The combination, with a pair of knobs, a spindle, and a latch, of an indicator-disk in one of the knobs, a button in the other, a shaft connecting the two, pins in the shank of one of the knobs adapted to lock or unlock 35 the latch, and means for operating the pins, substantially as set forth.

4. The combination, with a lock having a latch therein and a pivoted post upon which the latch is mounted, of a spindle fitted in the post, knobs on the ends of the spindle, an 40 indicator-disk in one knob, a button in the other, a shaft connecting said disk and button, pins adapted to enter recesses in the lock and post for fastening the latch, and mechanism for operating said pins simultaneously 45 with the changing of the indicator, substantially as set forth.

5. The combination, with a lock having a pivoted spring-actuated latch and a pivoted post therein, of a spindle extending through 50 the post, a pair of knobs on the ends of the spindle, one of the knobs being slotted and having an indicator-disk therein and the other having a button, a shaft extending loosely through the spindle and having angular ends 55 which fit sockets in the disk and button, sliding pins in the shank of the inner knob adapted to enter recesses formed partly in the lock and post, and cam mechanism whereby the pins and disk are simultaneously operated by turning the button, substantially 60 as set forth.

In testimony whereof I have signed this specification in the presence of two subscribing witnesses.

WILLIAM H. KING.
